UNITED STATES PATENT OFFICE.

EMIL MÖHRLIN, OF STUTTGART-DEGERLOCH, GERMANY, ASSIGNOR TO THE FIRM
MÖHRLIN G. M. B. H., OF STUTTGART, GERMANY.

TUBE BEADER.

Application filed March 6, 1925, Serial No. 13,487, and in Germany March 10, 1924.

My invention relates to means for simultaneously expanding and beading tube ends in flanges and the like in an easier and more efficient manner.

5 It has already been proposed to perform the expanding and the beading in a single operation and with the aid of a single tube beader, having rollers which at the same time permitted expanding and beading the 10 end of the tube in the flange hole.

However this mode of proceeding is unsatisfactory inasmuch as a conical mandrel inserted in the tube so as to gradually force the rollers against its walls will not 15 operate with bead rollers. Specially shaped mandrels are therefore required which not only increase the first cost of the beader and interfere with the facility of its operation but also involve the further drawback 20 that the beader cannot be used for tubes of as many different diameters as is possible with the usual beader. Moreover the products are inferior inasmuch as the diameters of the contacting surfaces are not equal.

25 In order to overcome this drawback it has been proposed to combine two sets of rollers of a different kind, one set performing the expanding, the other the beading of the tube ends, but in this case a ridge was 30 formed between the parts acted on by the different rollers.

It is an object of my invention to overcome these drawbacks and to provide a tube beader which may be used within a very 35 wide range of tube diameters and equipped with the usual conical mandrel, and is capable of performing the rolling-in and beading operations in a single operation and to perfection from the technical and economical 40 point of view.

My invention comprises the provision of a separate beading roller or rollers which are independent of the expanding rollers. The end face of the beading roller abuts 45 against the corresponding face of the adjacent expanding roller and the beading roller is arranged eccentrically to the expanding rollers, the eccentricity being so determined that on the inside of the set of rollers the beading and expanding rollers both rotate 50 on the conical surface of the mandrel while on the outside the beading roller projects beyond the expanding rollers. In this man-

ner the beading roller on the one hand and the expanding rollers on the other hand 55 are free to rotate as required for the operation to be performed by each of them and at the same time they are supported by the mandrel which may be of the usual conical form and of any suitable length.

60 In the drawings affixed to this specification and forming part thereof, two devices embodying my invention are illustrated diagrammatically by way of example.

65 In the drawings,

Fig. 1 is a side elevation, partly in longitudinal section along the axis of one set of rollers,

Fig. 2 is an elevation, partly in section, showing the arrangement of the set of rollers,

Fig. 3 is a cross-section on line 3—3 in Fig. 2,

Fig. 4 is a diagrammatic elevation illustrating a modified method of roller support, 75 and

Fig. 5 is a cross-section on line 5—5 in Fig. 4.

Referring first to Figs. 1 to 3, *a* is the head 80 of the implement to which rotation is imparted by suitable means (not shown). The head is provided with radial guides *a*¹, in which slides *b* are mounted for reciprocation. Pins *c* are secured to the guides and expanding rollers *d* and a beading roller *e* is 85 rotatably mounted on the pin and retained on the pin by a head *c*¹. The beading roller *e* is free to rotate independently of the rollers *d* and is seated on an eccentric bush *f* which is held on the pin *c* by a set screw 90 *f*¹. The eccentricity of the bush *f* is so determined and the bush is so adjusted that on the outside of the set of rollers the beading roller *e* projects beyond the expanding 95 rollers *d* so that the desired section is obtained at the end of the tube, while on the inside all the rollers are in contact with the mandrel *g*. The mandrel is advanced into the tube during the operation in the usual manner.

100 The modification here described is particularly suitable for tubes of comparatively large diameter. For tubes of small diameter the modification disclosed in Figs. 4 and 5 is preferred. Here holders *h* are secured 105 on the ends *c*² of the pins *c* which are mount-

ed in slides on a head such as described with reference to Figs. 1 to 3, but for the sake of clearness these parts are not shown in Fig. 4. The holder h is provided with a yoke-shaped extension h' in which are mounted the expanding rollers d' and the beading roller e' . The rollers rotate in contact with the mandrel g as described and balls i, i' may be inserted between the ends of the rollers and the corresponding ends of the yoke h' .

I wish it to be understood that I do not desire to be limited to the exact details of construction shown and described, for obvious modifications will occur to a person skilled in the art.

I claim:

1. Tube beader comprising a head, a radial guide on said head, a slide adapted to be displaced in said guide, an expanding roller and a beading roller rotatably carried on said slide, said beading roller being mounted ec-
20

centrically with regard to said expanding roller, and means for transversely displacing said rollers and said slide. 25

2. Tube beader comprising a head, a radial guide on said head, a slide adapted to be displaced in said guide, a pin secured to said guide, an expanding roller mounted on said pin, a beading roller eccentrically mounted 30 on said pin, and means for transversely displacing said rollers and said slide.

3. Tube beader comprising a head, a radial guide on said head, a slide adapted to be displaced in said guide, a yoke secured on 35 said slide, and expanding roller and a beading roller mounted in said yoke, said beading roller being mounted eccentrically with regard to said expanding roller, and means for transversely displacing said rollers and said 40 slide.

In testimony whereof I affix my signature.

E. MÖHRLIN.
